UNITED STATES PATENT OFFICE

MARTIN E. JOHNSON, OF CHICAGO, ILLINOIS, ASSIGNOR OF ONE-HALF TO IRA J. WILSON, OF WINNETKA, ILLINOIS

PIPE BENDER

Application filed June 13, 1929. Serial No. 370,474.

This invention relates to pipe bending devices of the type suited either for attachment to a bench, scaffold or other support, or for use as a hand implement.

It is frequently necessary in modifying existing conduit installations or in running new installations to bend the conduit while in place against a ceiling or wall. This requires a bender which will grasp the conduit while it is against the ceiling or other support in such a manner that the conduit may be bent in the direction desired. Also heretofore it has been customary to use different devices for bench and hand work, thus making it imperative to carry two pipe benders or "hickies" when upon an installation away from the shop. In the prior devices of the bench type benders suitable for use on scaffolds or ladders and which were usually attached to the supporting ladder or standard, no provision was made for bringing the work within reach of the workman. In such devices it is necessary for the workman to reach over the side of the scaffold in an awkward and dangerous manner. Furthermore, no provision was made to facilitate handling the work after a partial bend was made, causing the end of the pipe being bent to extend out of reach of the workman.

It is the purpose of this invention, therefore, to provide a single device which may be used for bench or hand work, which may be used flush against a ceiling or other support, which will support the work in a position readily reached by the workman when the device is secured to a scaffold or ladder and which will support the work in such a manner as to assist in making short bends.

In accordance with this invention the pipe bending device is constructed principally of two parts, one a supporting plate member and the other a bending member, the latter of which carries the usual spaced pipe engaging portions or elements over which the pipe may be bent when using the device in the open or away from the pipe support. The latter member is also provided with means for grasping a pipe or conduit which is supported tightly against a ceiling or other support and with means for attachment of two handles

when the member is to be used alone as a hand device. In this instance one handle may be used as a fulcrum while the other handle may be used to impart a bending movement to the bending member as a whole. The two members are also constructed to be detachably locked together in order that they may be separated for individual use and interlocked in such a manner that they may be separated at will and replaced together in any of several positions with their principal surfaces either in the same or in different planes. This manner of attachment of the two parts makes it possible to bring the work within convenient reaching distance of the workman in the event that the supporting plate member is secured to a scaffold or the like, or in the event that short bends are being made.

In one form the interlocking means on the bending member may also serve as the conduit gripping element when conduit against a ceiling is to be bent.

Other advantages and novel points of structure will be apparent from the following description of one embodiment of this invention given in connection with the drawings, in which:

Fig. 1 is a plan view of a pipe bender constructed in accordance with this invention and applied to the upright of a ladder,

Fig. 2 is a front elevation of a pipe bender constructed in accordance with this invention,

Fig. 3 is a side elevation of the same,

Fig. 4 is a front elevation of the supporting plate member,

Fig. 5 is a side elevation of the bending member showing the disposition of the two handles for use as a hand device, and

Fig. 6 is a rear elevation of the bending member.

In the illustrated embodiment of this invention the bending device or "hickey" is one particularly suitable for bending oval conduit and is constructed of two main members, a supporting plate member indicated generally by reference numeral 1 and a bending member indicated generally by reference numeral 2, the two members being detachably secured together by a form of

tongue and groove connection to be later described.

The supporting plate member 1 is generally an elongated flat member adapted to be secured to a bench scaffold, ladder (Fig. 1) or the like by means of bolts passing through openings 3 at each end of the plate. Formed integrally with and extending the full length of the plate is an upper and lower track or guideway 4 and 5 respectively the edges of which are undercut as at 6 (Fig. 1) to form one member of a tongue and groove or dovetail sliding connection between members 1 and 2 to be described more fully hereafter. The upper section of the track or runway 4 is inclined to the general plane of plate 1, i. e., the outer surface of track 4, if continued, would intersect the rear face of plate 1, as is clearly shown in Fig. 1. This inclination throws the member 2, when attached to the plate member, inwardly, and thus brings the work within reach of the workman, as will be more fully explained hereafter. The lower track 5 is formed with its outer face parallel to the general plane of plate 1 (Fig. 1), thus affording two positions for the bending member when attached in different planes. At the juncture of the two tracks there is formed a shoulder 7 which acts as a limiting stop of the upper track.

The bending member indicated generally by reference numeral 2 has the shape of a flat square member having two channels or grooves 8 formed in one face thereof. The grooves are of sufficient depth and width to fit over the conduit for which the bender is designed. The grooves also serve as the other member of the sliding connection between parts 1 and 2 and for this reason the outer edges of the grooves are extended inwardly to engage the undercut edges of either track 4 or 5 and to interlock therewith. The channels in the illustrated form extend across the entire member in directions perpendicular to each other, thus the bending member can be removed from the supporting plate rotated 90° and be reassembled with the other channel engaging the track. Projecting from the member 2 on the opposite face from that having the channels 8 are a pair of spaced pipe engaging elements 9 and 10 also grooved to receive the size pipe or conduit for which the bender is designed. As is customary, the elements 9 and 10 may be staggered to permit the member being placed sidewise over the pipe to be bent.

To facilitate use of the bending member independently of the supporting plate and as a simple hand device, the bending member is formed with a projecting socket 12 the center of which is substantially on the plane of the axes of the grooves in elements 9 and 10 removed from the plane of the axis of grooves 8. Socket 12 is drilled and tapped in a direction parallel to the general plane of

the bending member to receive a handle 13 such as a short length of pipe. This handle is adapted to serve as a lever for imparting a bending movement to said member. The socket 12 may also have a lateral extension 14 on one side thereof tapped to receive a second handle 15 which will extend in a direction perpendicular to the first handle. The handle 15 may be used as a means of removing and replacing the bending member from and on the supporting plate member, and it may also be used as a fulcrum when the device is being used as a hand implement.

In practice the pipe bender may be used as a bench device by which is meant either a bench or scaffolding of any type, or as a hand implement. For the first use the supporting plate member 1 is attached to a bench or other support by means of bolts or screws fastened through holes 3, the upper hole being countersunk to permit the head of the securing bolt or screw to be sunk flush with the top surface or track 4. The bending member may then be slid on track 4 until the bottom edge of the bending member contacts with the shoulder 7. In this position the axes of the two grooves in the pipe engaging elements 9 and 10 will be inclined to the general plane of the plate member 1, thus causing a piece of pipe held therein to project over the platform or scaffolding in such a manner that it may be conveniently grasped by the workman. Should the section of pipe being bent be too long or in the way projecting over the scaffold, the bending member may be removed from track 4 and replaced by sliding upon track 5. In this position the axes of the grooves in pipe engaging elements 9 and 10 are substantially parallel to the general plane of the supporting plate member. If the character of the bend being made in the pipe carries the projecting portion of the pipe vertically out of reach of the workman before the bend has been completed, the bending member may be removed from track 4 or 5, rotated 90° and replaced with the other channel engaging the particular track desired, thus bringing the projecting portion of the pipe back within reach of the workman. For use as a hand device the member 2 is used independently of the supporting plate 1. In this use handle 13 is used as a lever while handle 15 may be used as a fulcrum. Where the pipe being bent is not in close relation to a ceiling or the like elements 9 and 10 may be used for grasping the pipe. If the pipe to be bent is secured against the ceiling or the like grooves 8 may be used thus permitting the element to be placed flush against the ceiling. In this use it is to be noted that although the face of the bender may be flush against the ceiling handle 13 is spaced far enough away to permit grasping by the hand but is near enough so that the bender is not likely to skew around.

From the above it is obvious that a pipe bending device constructed in accordance with the principles of this invention is capable of varied uses and of application in places of limited spaces. It is also apparent that a device constructed in accordance with this invention brings the pipe or conduit being bent to a convenient and safe position for manipulation by the workman. It is obvious that other forms of interlocking tracks may be used in place of the simple tongue and groove slide shown and that other changes may be made in the details of construction without departing from the spirit and scope 15 of this invention as defined in the claims appended hereto.

I claim:

1. A pipe bender adapted for use as a hand device or as a bench device including a supporting plate member, a bending member, said bending member having a plurality of spaced pipe engaging portions projecting therefrom, said pipe engaging portions having grooves therein disposed with their axes substantially aligned with each other and by means of which a section of pipe may be bent, and means for detachably securing said bending member to said supporting plate member with the axes of said grooves at an inclination to the plane of said supporting plate.

2. A pipe bender adapted for use as a hand device or as a bench device including a supporting plate member, a bending member, said bending member having a plurality of pipe engaging portions projecting therefrom in spaced relation to one another and over which a section of pipe may be bent, and a tongue and groove sliding connection between said supporting plate member and said bending member, whereby said members may be detachably secured together.

3. A pipe bender adapted for use as a hand device or as a bench device including a supporting plate member, a bending member, said bending member having a plurality of spaced pipe engaging portions projecting therefrom and over which a section of pipe may be bent, and means for detachably securing said bending member to said supporting plate member with the plane of said bending member at an inclination to the plane of said plate member.

4. A pipe bender comprising a bending member having a plurality of spaced pipe engaging portions projecting therefrom over which a section of pipe may be bent, means for attaching a handle to said member, and means for attaching a second handle to said member in such a manner that the two handles will extend in different directions from said member when attached thereto, whereby one handle may be used as a fulcrum for movements produced in said member by the use of said second handle.

5. A pipe bender comprising a supporting

plate member and a bending member having spaced pipe engaging portions projecting from one face thereof arranged to simultaneously engage the opposite sides of the pipe being bent at spaced points along its length, means for securing said bending member to said plate member in a plurality of positions angularly disposed relatively to each other.

6. A pipe bender comprising a supporting plate member and a bending member, said latter member having spaced pipe engaging portions projecting therefrom arranged to simultaneously engage the opposite sides of the pipe being bent at spaced points along its length, means for securing said bending member to said plate member in two positions in substantially the same plane but angularly disposed relatively to each other.

7. A pipe bender comprising a supporting plate member and a bending member, said latter member having spaced pipe engaging portions projecting therefrom arranged to simultaneously engage the opposite sides of the pipe being bent at spaced points along its length, means for securing said bending member to said plate member in two positions in different planes.

8. A pipe bender comprising a supporting plate member having a track member formed thereon and a bending member, said latter member having a plurality of spaced pipe engaging portions projecting therefrom and having a plurality of channels formed therein, said channels being disposed at an inclination to each other, each of said channels being constructed to engage and interlock with said track whereby said bending member may be secured to said plate member in a plurality of angular positions in substantially the same plane.

9. A pipe bender comprising a supporting plate member having a track formed thereon and a bending member having a plurality of spaced pipe engaging portions projecting therefrom, and having a channel formed therein constructed to engage and interlock with said track, said track having a plurality of sections, each section being disposed in a different plane relatively to the other sections whereby said bending member may be secured to said plate member in each of a plurality of positions in relatively different planes.

10. A pipe bender including a bending member having pipe engaging grooves in one face thereof and a handle projecting from another face thereof with the axis of said handle parallel to the axes of said grooves but in a plane removed from the plane of the axis of said grooves whereby the face of the bending member having pipe engaging grooves therein may engage a pipe in contact with its supporting surface without removing the pipe therefrom.

11. A pipe bender including a bending

member having means for securing a handle thereto a plurality of spaced pipe engaging portions projecting from one face thereof and over which a section of pipe may be bent and a pipe engaging groove in another face thereof.

12. A pipe bender adapted for use as a hand device or as a bench device including a supporting plate member, a bending member, said bending member having means for securing a handle thereto, a plurality of spaced pipe engaging portions projecting from one face thereof and over which a section of pipe may be bent and pipe engaging

15 grooves formed in another face thereof and means for detachably securing said bending member to said supporting plate member.

13. A pipe bender adapted for use as a hand device or as a bench device including 20 a supporting plate member, a bending member, said bending member having a plurality of spaced pipe engaging portions projecting from one face thereof and over which a section of pipe may be bent and having pipe 25 engaging grooves formed in another face thereof and means for detachably securing said bending member to said supporting plate member, said grooves constituting one element of said securing means.

30 14. A pipe bender adapted for use as a hand device or as a bench device including a supporting plate member, means for securing said plate member to a support, and a bending member detachably secured to said plate 35 member, said bending member being removable from said plate member independently thereof and having a plurality of spaced pipe engaging portions projecting therefrom and over which a section of pipe may be bent and 40 means for securing a handle thereto whereby said bending member may be used independently of said supporting plate member without disturbing the attachment of the plate member to its support.

45 In witness of the foregoing I affix my signature.

MARTIN E. JOHNSON.
